UNITED STATES PATENT OFFICE

THOMAS J. BURKE, OF NEW ORLEANS, LOUISIANA

SALVAGING EQUIPMENT

Application filed January 28, 1928. Serial No. 250,218.

My present invention relates to an improved salvaging equipment designed for submarine employment in raising or lifting sunken or submerged marine craft and especially adapted for use in raising submersible vessels. In carrying out my invention, I utilize one or more submersible buoyant pontoons that are especially constructed to facilitate their submersion for attachment to the sunken craft, and further to raise or lift the submerged craft. While I have illustrated only one buoyant submersible pontoon, it will be understood that as many pontoons may be used in operating with the equipment of my invention as are necessary. In combination with the specially constructed pontoon, I utilize a well known type of link-chain as a guide when lowering the pontoon, and the same chain is utilized as the medium by which the buoyant pontoon raises the submerged craft to the surface of the water. Means are employed on the pontoon for automatically attaching and locking the pontoon to the guide chain when the pontoon has reached the required depth preparatory to lifting the sunken vessel. By the utilization of the equipment of my invention, a pontoon may with convenience and facility be lowered and attached to a sunken vessel, and then the latter may be lifted by the buoyant pontoon to the water surface without undue loss of time.

The invention consists in certain novel combinations and arrangements of parts as will hereinafter be more fully described and claimed.

In the accompanying drawings, I have illustrated one complete example of the physical embodiment of my invention as used for the purpose of raising a sunken submarine vessel, it being understood that the necessary number of pontoons are of course employed as the tonnage of the submarine requires.

Figure 1 is a view showing the equipment of my invention in use in connection with a sunken submarine showing a pontoon in position for use in raising the vessel;

Fig. 2 is a view showing a pontoon in cross section attached or coupled to a lifting chain

which is shown as connected with a suitable portion of a vessel to be raised;

Fig. 3 is a longitudinal section of a pontoon according to my invention showing its relation to the guide-lifting chain with the parts in position as the pontoon is being lowered;

Fig. 4 is an enlarged detail view showing the relation of a pair of sprocket wheels carried by the pontoon to the guide-lifting chain;

Fig. 5 is a top plan view of the sprocket wheels of Fig. 4 showing a link of the chain in cross section; and

Fig. 6 is a cross sectional view at line 6—6 of Fig. 3.

Figure 7 is a detail view showing a modified form of clutch for use with a guide-lift cable.

In carrying out my invention, I use a submersible buoyant pontoon of any suitable type, herein illustrated as a cylinder 1 having closed ends or heads 2 and 3. Any suitable type of pontoon may be used, and of course any suitable number of pontoons may be used in carrying out my invention. The pontoon is submerged by first opening a water intake valve 4 at the underside of the pontoon and this valve may be operated through the stem 5 that passes transversely through the pontoon and the control wheel or handle 6. The handle is manipulated when the pontoon is at the water surface for the purpose of admitting water to the interior of the pontoon so that it may be submerged.

An air hose 7 extending from a suitable pump on the tender or surface vessel V, is connected at the top portion of the pontoon by an air inlet valve 8, and the interior of the pontoon may be vented through valve 6' as the water is admitted to the water valve 4. The pontoon is provided with an outlet water valve 9 which has a pipe 10 extending from the top of the pontoon and terminating near the bottom of the pontoon.

As the air is forced into the interior of the pontoon through the hose 7, it will be apparent that the water is forced out through the pipe 10 and outlet valve 9 for the purpose of rendering the pontoon buoyant.

Thus the pontoon may be lowered to a sunken submarine as S by the admission of water to submerge it, and when the pontoon is to perform its lifting functions, the water is forced out of the pontoon and air is forced therein as is customary.

Within the interior of the pontoon, I arrange a centrally disposed transverse tube 11 which has open ends and which is designed to encircle or surround a chain C which is made up of usual type of links 12 and 13. This chain is threaded through the cylindrical pontoon and may be passed through the tube from the upper end or from the lower end of the tube. The chain is used as a guide for the pontoon when it is being lowered and after the pontoon has been attached to the sunken vessel S then the chain is used as a lift chain in connection with the buoyant pontoon.

At the upper and lower ends of the tube 11 of the pontoon, I provide a pair of sprocket wheels 14 which are preferably of the same size and shape and each wheel is fashioned with alternately arranged single teeth 15 and double spaced teeth 16 that are adapted to engage the alternate links 12 and 13 of the chain C. These sprocket wheels which are arranged in complementary pairs are supported in brackets 17 and the shafts 18 of the wheels are journaled in these brackets so that the sprocket wheels will revolve readily as the pontoon descends and by the use of these pairs of sprocket wheels co-operating with the links of the chain, the pontoon is guided and is prevented from swinging or swaying, and of course is retained in its proper relation to the chain.

Within the tube 11 are provided a suitable number of pawls 19 which are preferably arranged at spaced intervals around the interior periphery of the tube and these pawls are pivoted at 20 on spaced rings or bands 21 fixed to the interior of the tube. These rings 21 are spaced apart, and four of them are shown in Fig. 3, each ring being provided with a spring pressed pawl that is pivoted at the upper side of the ring. The four pawls are arranged 90° apart, and two pawls are adapted to engage two spaced chain links, while the other two pawls are adapted to engage alternate spaced chain links. Thus while the pontoon is descending as in Fig. 3, the free ends of the pawls ride along the links of the chain, but when the pontoon stops its descent, the pawls are designed to fall by gravity and aided by the springs as indicated by dotted lines in Fig. 3 and the free end of each pawl slips through a complementary link of the chain, and then the free end of the pawl rests upon the top face of its supporting ring. Thus the pontoon is securely locked to the chain and if the pontoon has sufficient buoyancy, it will rise to the surface of the water carrying with it that portion of the chain sus-

pended below the transversely arranged locking pawls, and of course the craft to which the lower end of the chain is fastened will also be raised as the pontoon rises. Thus the pontoon may be lowered to a predetermined depth and held stationary so that its locking pawls will engage the complementary links of the chain. Then the water may be pumped out of the pontoon and air substituted therefor to render the pontoon buoyant. The buoyant pontoon may then lift the object below it a predetermined distance, and this performance may be repeated until the sunken object is raised step by step to the surface. In other instances, a sufficient number of pontoons may be employed to lift the sunken craft in one operation, and of course many other variations in the use of the pontoons may be introduced.

In Fig. 1, the tender or surface vessel V has lowered one of the pontoons to the sunken submersible or submarine boat S and the pontoon is illustrated in position to lift the sunken submarine. In Fig. 2, a portion of a safety box is indicated at 22 as built into the hull of the submarine S and the hatch or lid 23 of this safety box is shown open so that a grappling hook 24 forms the connection between the chain C and the submerged craft S. This connection also includes an air motor 25 used in connection with the grappling hooks, and an air hose 26 from the vessel V extends down from the rescue vessel V, shown in Fig. 1, and short hose connections 27 and 28, together with the grappling hooks 24 provide means whereby air, liquid food, water, &c. may be introduced to the interior of the submerged submarine from the surface vessel V.

It will be apparent that the equipment of my invention may be used in many different ways, and I of course contemplate these various uses. The structure shown is an exemplifying structure and it will be apparent that I may make changes in the construction and operation of the equipment within the scope of my claims without departing from the principles of my invention.

For instance, when a cable 29 in Figure 7 is substituted for the guide-lift chain, a pair of grooved pulleys 30 are arranged at the upper and lower ends of the tube 11 instead of sprocket wheels, and a pair of clutch shoes 31 for frictional engagement at opposite sides of the cable, are pivotally supported by pairs of links 32 from the inner face of the wall of the tube 11.

The guide pulleys, and especially the pairs of sprocket wheels, are specially adapted to maintain the proper relation between the pontoon and the chain, so that the pawls will always be in position to slip into the links of the chain.

It will be apparent that the pontoon may be lowered to depths that are inaccessible to divers, and when lowered to a sunken vessel,

the pontoon, is automatically coupled or attached to it for lifting purposes, thus entirely dispensing with the necessity for use of divers.

Having thus fully described my invention, what I claim as new and desire to secure by Letters Patent is—

1. The combination with a guide-lift chain, of a submersible pontoon having a tubular part surrounding the chain, of a pair of sprocket wheels at the opposite open ends of said tubular part, said wheels having alternately arranged single and double teeth for coaction with adjoining links of the chain, and means carried by the pontoon for coaction with the links for locking the pontoon to the chain.

2. The combination with a guide-lift chain, of a pontoon having a tubular part surrounding the chain, a pair of guide sprocket wheels at each open end of the tubular part, said sprocket wheels having alternately arranged single and double teeth for coaction with adjoining links of the chain, and a plurality of pivoted lock latches carried by the pontoon for coaction with the links of the chain.

3. The combination with a submersible buoyant pontoon having a transversely arranged open end tube and a guide-lift chain, of a pair of guide sprocket wheels journaled at each end of the tube, a plurality of spaced rings fixed within the tube, and a locking pawl hinged to each ring for co-action with the guide-lift chain.

THOMAS J. BURKE.
